UNITED STATES PATENT OFFICE.

ALPHEUS FAY, OF LOUISVILLE, KENTUCKY.

HOMOGENIZING APPARATUS.

1,019,953.

Specification of Letters Patent. Patented Mar. 12, 1912.

Application filed April 22, 1911. Serial No. 622,782.

To all whom it may concern:

Be it known that I, ALPHEUS FAY, a citizen of the United States, residing at Louisville, in the county of Jefferson and State 5 of Kentucky, have invented a certain new and useful Homogenizing Apparatus, of which the following is a specification.

The object of my invention is to produce a simple, economical, device for treating 10 substances to be merged into a single homogeneous mass, or homogenized, and is principally designed for use in producing such a product by the combination of butter, or a similar food substance, with milk, according 15 to a formula and by a process hereinafter to be more particularly described.

It is especially the object of this invention to so economize in the manufacture of the apparatus, while at the same time not sacrificing 20 any of the efficiency required, as to bring its cost low enough, and the care necessary in its operation to such a minimum, that it will be well adapted for domestic use.

In the drawings: Figure 1 is a sectional elevation of my apparatus. Fig. 2 is a plan view of the lid with attached parts. Fig. 3 is a detail perspective view of the brake. Fig. 4 is a plan view of a modification of my apparatus. Fig. 5 is a sectional elevation 30 of the apparatus as shown in Fig. 4. Fig. 6 is a sectional elevation of another modification of my apparatus. Fig. 7 is a partial plan view of the lids of the apparatus shown in Fig. 6, and with the bearing head thereof shown in section on a line $x-x$ of Fig. 6, also indicating the brake in position on the lower side of the main lid by dotted lines. Fig. 8 is a detail perspective view of the brake of the apparatus shown in Figs. 6 and 7.

40 The general construction of my apparatus involves the combination of an outer vessel and an inner vessel, a dasher with vertical axis inside the inner vessel, a brake disposed vertically at one side of the vessel to coact 45 with the dasher, means for supporting the inner vessel in the outer one so that an efficient water bath may be maintained between them, and means for rotating the dasher.

With a view to most effectively accomplishing the economical production of the 50 apparatus, it is desired to entirely dispense

with finishing operations upon any of the parts of the device, making them in the form of castings that will fit to each other and to the vessels without any considerable 55 care in adjustment and without the finishing operations referred to. This requirement is met in all of the examples illustrated.

In the example illustrated in Fig. 1, the 60 outer vessel 1 is shown to be of seamed construction, as is also the inner vessel 2, and this inner vessel 2 has its shell carried down below its bottom and suitably perforated, so that there may be circulation of water under 65 the vessel 2. Above, the lid 3 is supported on the rim of the outer vessel 1 and bears down on the rim of the inner vessel 2, having beads on its lower side to engage with 70 said rims and maintain the proper relative positions of the vessels. This lid 3 is of openwork formation as is best seen in Fig. 2, and centrally it carries a bearing head 4, formed integral with it, this bearing head 75 overhanging a rectangular opening in the lid up through which the dasher shank 5 extends to have an upper bearing 5^a in the lower side of said head. This shank 5 carries the pinion 6 rigidly mounted on it directly below this bearing; this pinion may 80 be forced on the shank. A driving shaft 7 is, as illustrated, integral with the crank 8, and is horizontally journaled in the head 4, above the upper end of the shank 5. A gear 85 wheel 9 is forced onto this shaft 7, to have a bearing against the adjacent side of the head, preventing end thrust of the shaft. An auxiliary bearing bracket 4^a bears 90 against the end of the shaft 7 beyond the gear 9. The gear 9 meshes with the pinion 6, they being of bevel design for this purpose. The brake 10 comprises a vertical column with a flattened upper end 10^a that extends up through a slot in the lid, there being lugs 3' on the upper side of the lid 95 embracing the flattened upper end 10^a where it extends above the lid 3. At its lower end this column 10 has a foot 10^b that extends radially over to the center of the shank 5 of the dasher and has a step bearing 10^{b'} for 100 the lower end of said shank. This foot rests snugly against the bottom of the vessel

2. The upper end of the shank 5 bears up against the upper end of its bearing 5^a in the head 4. Thus, the dasher is supported for rotation and its end play up and down is limited by the coöperation of the brake with its step, below, and the head 4, above. The brake has its operative parts composed of radially inwardly projecting bars 10^c, and the dasher has its operative parts composed 5 of bars 5^b, projecting radially from it in opposite directions, and adapted to swing around between the bars of the brake; by this coöperation of the bars of the dasher and of the brake, respectively, a disruption 10 of the body of substances in the vessel 2 is effected and the mixture of various substances is induced by constant disruption and collision of the particles of the respective substances.
- 15 In assembling the device for operation, the upper flattened end of the brake column is slipped into the slot of the lid after the upper end of the dasher shank is inserted into its bearing in the head, and the step bearing on the foot of the brake receives the 20 lower end of the shank, upon which the entire operative device is lowered into the vessel 2 and the lid 3 engages with both vessels 1 and 2, alining them and holding them in 25 their alined positions. Then the lid is manually held down while the crank or handle 8 is turned. In taking the finished product from the vessel, the lid 3 is lifted off, leaving the dasher and brake in the vessel 2 to be 30 withdrawn singly, as is desirable, owing to the adhesion of the product to these parts. The product may be thus conveniently scraped from the dasher and brake with the lid removed.
- 35 In the modification shown in Figs. 4 and 5, the vessels 11 and 12 are shown as seamless, and the inner vessel 12 is suspended in an outer lid or ring 13 that rests on the rim of the outer vessel 11 and receives the bead 40 of the upper rim of the vessel 12 on an interior flange 13'. This leaves the space between the vessels entirely unobstructed. An inner lid 13^a rests on the rim of the inner vessel 12, inside the ring 13, and this lid 13^a has the bearing head 14 integral with it. The lid 13^a has a central opening, and the shank 15 of the dasher has the pinion 16 forced onto it, down against a flange 15' integral with the shank 15. The opening in 45 the lid 13^a is preferably just sufficiently large to allow the pinion 16 to pass up through it, and the flange 15' is just large enough to close the opening when the parts are assembled. The driving shaft 17 has 50 the crank 18 fitting onto an angular part at its end, and the shaft may be integral with the gear 19, which is located outside the bearings of the shaft 17 in the head 14. A handle 14^a spans the space between the bearings, and forms a convenient means of hold-

ing the apparatus together when operated. The flattened upper end 20^a of the brake 20 extends into a socket in the head in the same manner as in the example above described. The brake also has a foot 20^b on the lower end of its column, with a step bearing for the shank 15. The bars 20^c and 15^b of the brake and of the dasher, respectively, coöperate as above described.

In the example shown in Figs. 6 to 8, inclusive, the parts are the same as those of the example of Figs. 4 and 5 just described, excepting that the brake 20 has no foot and the dasher shank 15 is unsupported at its lower end. Instead, a bracket 20^d extends 75 radially over and has a fork embracing the shank 15 immediately under the lid 13^a, and the pinion 16 has its hub extending down through the opening in the lid and bearing on this fork, thus supporting the dasher. 80 The brake is supported by means of a set screw taking in through the head against the flattened upper end 20^a in the socket in the head, instead of having the brake supported on the bottom of the vessel 12. The 85 opening through the lid 13^a is located somewhat out of alinement with the shank 15, so that it admits the pinion to pass above the lid, and then sidewise to pass the upper end of the shank 15 into its bearing 15^a, upon 90 which the hub of the pinion bears against the side of the opening in the lid adjacent where the fork of the bracket 20^d is open, thus completing the lower bearing of the dasher shank. This arrangement, by dispensing with the step on the bottom of the vessel allows the dasher to operate closer to the bottom of the vessel, and also lessens the 95 number of parts for the product to cling to, thus facilitating the removal of the product 100 after completion of the operation.

The latter two examples are adapted to form substantially closed tops to the vessels, and are thus shown, but it will be understood that they may also be used with the 110 open-topped method of treatment. It is generally advantageous to have the top of the inner vessel open, so that the progress of the operation may be observed readily.

Homogenized preparations may be produced to be used as butter, or as oleomargarin, or as butterin. In either case, the butter, or the oleomargarin, or, in the case of butterin, lard, is taken in equal quantity by weight, with the milk, and the mixture placed in the inside vessel with the milk at a temperature of about 50 degrees Fahrenheit, and the fatty ingredient, butter, oleomargarin, or lard, as the case may be, at any of the usual temperatures. Hot water may then be supplied to the outer vessel, and the apparatus may be placed over a source of heat, or the heat of the water alone being relied upon to produce the desired result. In any case, the heat of the water, or of the wa- 115 120 125 130

ter combined with the other source of heat, should be sufficient to raise the temperature of the mixture in the vessel to about 90 degrees Fahrenheit, in about three minutes. During this three minutes, the agitation, with the consequent disruption and collision of the particles of fatty substance and of the milk, is kept up, and at the end of the time, the butter, or oleomargarin, or lard, as the case may be, will be found to have merged with the milk into a single homogeneous mass, having the characteristics of butter, or oleomargarin, or lard, as the case may be, and well adapted for use as such by the users of the apparatus. When properly labeled, this homogenized article is also marketable, although it will be understood that this extremely simple, inexpensive, conveniently operated device is best adapted for the use of the consumer, operating with such capacity that comparatively small quantities of the product are made, to be used in the household where it is made. Marked economy is allowed, since the cost of the product is only the mean between the cost of the butter, or other fatty ingredient, and the cost of the milk. Furthermore, such homogenized products are superior to their pure fatty ingredients, inasmuch as they contain milk solids not found in the pure fatty substances alone. Such apparatus makes available to the consumer, in small, inexpensive quantities, these products, which ordinarily would be produced with facility only on a large scale.

It will also be understood that my apparatus is adaptable for operations of a similar nature on kindred substances, such as churning milk or cream to extract butter, or in mixing various substances for culinary purposes.

Having fully described my invention, what I claim as new and desire to secure by Letters Patent is:

1. In a device of the character described, a vessel, a dasher with vertical axis, a lid to the vessel having an upper bearing for the dasher integral with said lid, said bearing limiting the upward movement of the dasher, and a brake in the vessel, held in position by said lid, and engaging to limit the downward movement of the dasher.

2. In a device of the character described, the combination of a lid with a socket, and a brake having a flattened end part entering the socket, a vessel, and a dasher held for rotation on a vertical axis in the vessel and to coöperate with the brake, said lid having a part to limit upward movement of the dasher, and said brake having a part to limit downward movement of said dasher.

3. In a device of the character described, the combination of a lid, a dasher with a pinion rigidly attached to it near its upper end, said lid having a part forming an up-

per bearing for the dasher so that it may rotate on a vertical axis but be limited against upward movement, the lid and the part forming the bearing being integral and the lid having an opening to allow the pinion to pass up through it in the journaling of said dasher, and a brake held by the lid and forming a second bearing for the dasher and preventing downward movement of the dasher.

4. In a device of the character described, the combination of an outer vessel, an inner vessel, a dasher, a brake, and a lid having, integrally formed, means for supporting the brake, means for holding said vessels against relative displacement, and means for journaling said dasher, the brake also supporting the dasher and being removable from the lid to allow separation of the dasher from the lid, substantially as and for the purposes set forth.

5. In a device of the character described, as a new and improved article of manufacture, a lid for a vessel having, integrally formed, a horizontal shaft bearing, a downwardly opening vertical shaft bearing, and a downwardly opening socket displaced laterally from the vertical shaft bearing, and having an opening below said vertical shaft bearing of greater extent than that of the vertical shaft bearing, substantially as and for the purposes set forth.

6. In a device of the character described, as a new and improved article of manufacture, a lid for a vessel having, integrally formed, a main horizontal shaft bearing and an auxiliary horizontal shaft bearing, and having between the bearings a downwardly opening vertical shaft bearing, and, below said vertical shaft bearing, an opening of greater extent than that of said vertical shaft bearing, substantially as and for the purposes set forth.

7. In a device of the character described, the combination of an inner and an outer vessel, an outer annular lid for the outer vessel having an interior annular seat for the inner vessel, and a lid for the inner vessel having a bearing head formed integrally with it and fitting into the seat in the annular lid with said inner vessel, to hold said inner vessel in its seat.

8. In a device of the character described, the combination of an inner and an outer vessel, an outer annular lid for the outer vessel with an interior annular seat for the inner vessel, and an openwork lid for the inner vessel fitting into the seat in the lid of the outer vessel along with said inner vessel, to hold said inner vessel in its seat.

9. In a device of the character described, as a new and improved article of manufacture, a brake comprising, integrally formed, a column and a series of bars extending therefrom, and having an upper flattened

end part to said column, and an extension with a bearing for a shaft, for the purposes set forth.

10. In a device of the character described, 5 as a new and improved article of manufacture, a brake comprising a column and a series of bars extended therefrom arranged in succession from its lower end, and the

series discontinuing short of its upper end, and an extension adjacent its lowered end 10 having a bearing for a shaft.

ALPHEUS FAY.
